(57) **CLAIM**

The ornamental design for a combined bollard and light fixture, as shown and described.

DESCRIPTION

The patent or application file contains at least one drawing executed in color. Copies of this patent or patent application publication with the color drawing will be provided by the Office upon request and payment of the necessary fee.

FIG. 1 is a photograph of a perspective view of the combined bollard and light fixture, the right side being identical with the left side as shown and the back being identical with the front as shown, color but not the specific wavelength of light for the wash forming a part of the design, the color of the surface of the combined bollard and light fixture not forming a part of the design.

FIG. 2 is a photograph of a front view inclined from above of the combined bollard and light fixture, the back being identical with the front as shown, color but not the specific wavelength of light for the wash forming a part of the design, the color of the surface of the combined bollard and light fixture not forming a part of the design.

The bottom view does not form part of the design.
